UNITED STATES PATENT OFFICE

JOHN LLOYD, OF NOETH BRADDOCK, PENNSYLVANIA

METHOD OF PREVENTING THE FORMATION OF SCALE

Application filed August 28, 1931. Serial No. 580,044.

This invention relates to a method of preventing the adherence of scale to metal forming rolls. It is well known that when metal is heated to rolling temperature metallic oxides are formed on its surface in the form of a scale and that when such metal is passed through a rolling mill this scale sometimes adheres to the rolls thereof and leaves marks on the finished metal.

10 This invention is characterized by the fact that a secondary surface is maintained between the mill rolls and the metal being formed thereby, this preventing the adherence of scale to a marked degree. This is 15 preferably accomplished by continuously bathing the rolls with a coating fluid during the rolling operation. Such a coating fluid may be copper sulfate, potassium chromate, etc.

20 The accompanying drawing schematically represents one form of apparatus which may be used in the performance of the method incorporated in this invention.

Having reference to this drawing, there is 25 shown a stand of metal rolls 2 for the formation of a railroad rail. A double nozzle 3 is arranged over the top roll to thoroughly spray fluid over its rolling surface, this nozzle being connected through a pipe line 4 to a tank 5 and steam line 6. This steam line 6 is in connection with the top of tank 5 through a line 7 so as to equalize the pressure in this tank, the whole arrangement acting simply as an atomizer.

30 The tank 5 is filled with a coating fluid, through the funnel ended inlet 8, so that when steam is turned on the material will be ejected through the nozzles 3 in the form of a spray. A secondary surface may thus be maintained 35 between the top roll 2 and the metal being formed so long as it is bathed with coating material, making it impossible for scale to adhere to the rolls so treated.

In its more practical form the apparatus 45 shown would probably include a gage 9 for indicating the height of the material in the tank 5, and valves 10 and 12 would be interposed in the lines 4 and 7 at the points indicated to effect a control of the relative 50 amounts of steam and coating fluid ejected

through the nozzles 3. Valves 13 and 14 may also be advantageously inserted in the inlet 8 and the steam line 6 for obvious purposes. It might be added that the present specific description and drawing is in accordance with 55 the patent statutes, and not with the intention of limiting the scope of this invention exactly thereto, except as is defined by the appended claims.

I claim:

1. The method of preventing the adherence of scale to the surfaces of shaped rolls in hot rolling ferrous metal shapes which consists in maintaining a secondary surface on said rolls during the rolling operation to which the scale is non-adherent. 60

2. The method of preventing the adherence of scale to the surfaces of shaped rolls in hot rolling ferrous metal shapes which consists in maintaining a secondary surface composed of a coating of a chemical salt on said rolls during the rolling operation to which the scale is non-adherent. 65

3. The method of preventing the adherence of scale to the rolls of a hot-mill, consisting in continuously spraying the rolls with a metallic salt solution, whereby a secondary surface is maintained between the rolls and the metal being worked. 70

In testimony whereof, I have hereunto set my hand. 75

JOHN LLOYD.
